Salmon M. Prentice,
per Theo. Mungen,
Atty.

United States Patent Office.

SALMON M. PRENTICE, OF AURORA, ILLINOIS.

Letters Patent No. 94,238, dated August 31, 1869.

IMPROVEMENT IN FENCE.

The Schedule referred to in these Letters Patent and making part of the same.

To all whom it may concern:

Be it known that I, SALMON M. PRENTICE, of Aurora, in the county of Kane, in the State of Illinois, have invented a new and useful Improvement in the Construction of Fences; and I hereby declare the following to be a full, clear, and exact description of the construction of the same, reference being had to the annexed drawings, making a part of this specification, in which—

Figure 1 is a perspective view of the panels.

Figure 2, a detached view of the manner of fastening and connecting the same.

My invention consists in making fence-panels of any desired length of boards, scantling, poles, or rails, and wires, and upright pieces or battens, to which the boards, scantling, &c., are spiked or nailed. The uprights or battens are provided with holes midway between the rails, through which the wires are run laterally. The rails and wires are placed at proper distances apart, and any number of rails, wires, and battens may be used. The panels are constructed separately, and the middle or inner rail, or rails extend beyond the end batten of one panel to the centre of the second batten in the next one. All of the rails are of the same length. The wires are placed alternately between the rails, and extend from one end batten to the other end batten in the same panel, and are provided at each end with hooks. The panel is supported by iron braces, placed on opposite sides, and fastened through the top or upper end by an iron bolt to the same or alternate uprights or battens. The braces pass obliquely downward from the bolt, which fastens them to the batten, and enter the ground to a proper depth, and at a proper distance from the lowest rail, and are there hooked into and firmly held by a wedge or block of wood, or other suitable material. The panels are fastened together or connected by placing the end battens of two panels three or four inches apart, and spiking or nailing the middle or inner rail, or rails of one panel to the end batten of the next, and also spiking or nailing the end of the middle rail, or rails to the second batten of the next panel, and by placing wire staples with hooked ends, through holes in the end battens, and connecting the hooked ends of the staples, after crossing the ends of the staples, so as to bind the end battens together into the hooked ends of the wires that extend the full length of each panel, the wire staples with the hooked ends being placed midway between the rails, as are the wires in each panel.

To enable others to make and use my invention, I will proceed to describe its construction.

I construct the panels separately, using four uprights or battens, b c d e , three rails, a x z , and two wires, f , to each panel.

Two of the uprights or battens, b e , are placed at opposite ends, and two, c d , intermediately, the same distance from the end battens b e and from each other, the battens b d e being provided with holes h running laterally through them.

The rails a x z are of equal length; the ends of the top or upper rail a , and the bottom or lower rail z , being spiked or nailed to the end battens b e , while the end of the middle rail, x , is spiked or nailed, (although not shown in the drawing,) to the centre of the intermediate batten d , at o , and extends beyond the end batten b to the distance described between the centre of the intermediate batten d , at o , and the outer edge of the end batten e , at i .

The wires f are placed alternately between the rails a x z , and run through the lateral holes h in the batten d , and are provided with hooks s at each end.

The panel is supported by iron rods or braces u l , which are placed on opposite sides of it and fastened, by thrusting an iron bolt, provided with nut and screw, through holes made through upper end of the braces u l , the batten d , and the middle rail x , at w .

The braces are provided with hooks t , at their lower ends.

Passing obliquely downward from their fastening at w , the braces enter the ground about one foot from the lower rail z , penetrate it to a proper depth, and are there hooked into an opening, k , made in the upper surface of a wedge, y , of wood.

The wedge y is about eighteen inches in length, and three or four inches thick at the large or upper end.

The opening k , in the upper surface of the wedge y , should be made about three inches from the upper end, and should oblique inwardly and upwardly toward it, forming a kind of socket for the hooks t .

The wedge y should be driven into the ground, the point obliquing downward.

The braces u l extend about one foot below the lower rail z , and penetrate the ground to the wedge y , which is placed ten inches from the surface, thereby keeping the lower rail z two inches above the ground.

The wedge should be placed deeply enough to be beyond the influence of the frost and moisture, and to give stability to the fence. The depth depends, of course, upon the nature of the soil.

The panels B A are connected or fastened together by placing the edge of the end batten e of the panel B within three or four inches of the edge of the end batten b of the panel A , and spiking or nailing the middle rail x of the panel A to the end batten e of the other panel B , at p . Also spiking or nailing the end of the middle rail x to the centre of the batten d in panel B , at w , and also (see fig. 2) by placing wire staples, with hooked ends j , through the holes h in the end batten e of the

panel B, and the end batten *b* of panel A crossing the ends of the wire staples at *g*, so as to bind the end battens *e b* of the panels B A together.

The hooked ends *s* of the wires *f* are linked into or connected with the hooked ends *j* of the wire staples, thus firmly fastening or connecting the panels B A.

The space of three or four inches left between the end battens *e b* of the panels B A, is to give the flexion to the fence that is necessary on hilly or uneven ground.

As an equivalent for the hooked ends *t* and the wedge *y*, rings may be used at the lower ends of the braces *u l*, through which stakes or pins of wood should be driven, thus securing the fence to the earth in substantially the same manner.

To make the fence a portable one, no spike or nail should be used at the end of the middle rail *x* of panel A, where it meets the batten *d* of the panel B, but it should be held in place by the bolt at the fastening *w*. A bolt should also be used, in the place of spiking or nailing the same middle rail *x* of panel A to the batten *e* of the panel B, at *p*. Thus, by removing the

wire staples and the bolts at *w* and *p*, the panels are entirely disconnected.

What I claim as my invention, and desire to secure by Letters Patent, is—

1. The panels B A, when supported and secured to the earth by the braces *u l* and the wedge *y*, or their equivalents, and connected by the middle rail *x* and the wire staples, with hooked ends *j*, linked or connected with the hooked ends *s* of the wires *f*, constructed and arranged as herein shown and described.

2. Also, the mode of connecting fence-panels by wire staples with hooked ends *j*, crossed and linked or connected with the wires *f* at their hooked ends *s*, as herein substantially specified.

3. Further, the braces *u l* with hooked ends *t*, used in connection with the wedge *y*, or their equivalents, when used as a means of supporting and securing fences to the earth, as herein substantially specified.

SALMON M. PRENTICE.
